BY Victor J. Evans
ATTORNEY

UNITED STATES PATENT OFFICE

ROBERT L. SMITH, OF LYNCHBURG, VIRGINIA

ICE PICK

Application filed June 25, 1928. Serial No. 287,969.

This invention relates to ice picks and its general object is to provide a pick for chipping ice that can be used in a manner for chipping a piece of ice in substantially the size desired, as the penetrating point of the pick is retained in fixed position upon a cake of ice when the pick is put into operation, with the result the piece is broken away from the cake in a line from the point engaged by 10 the penetrating point.

A further object of the invention is to provide an ice pick of the sliding hammer type that has fastening means thereon to accommodate advertising matter and said means 15 also acts in the capacity of one of the stops for limiting the movement of the hammer in one direction.

Another object of the invention is to provide an ice pick of the character set forth, 20 that is simple in construction, inexpensive to manufacture and efficient in operation and service.

This invention also consists in certain other features of construction and in the combination 25 and arrangement of the several parts, to be hereinafter fully described, illustrated in the accompanying drawings and specifically pointed out in the appended claim.

In describing my invention in detail, reference will be had to the accompanying drawings wherein like characters denote like or 30 corresponding parts throughout the several views, and in which:

Figure 1 is a front view of the pick forming 35 the subject matter of the present invention.

Figure 2 is an edge elevation thereof showing parts in section.

Referring to the drawings in detail, the 40 numeral 1 indicates the shank of the pick, and formed with the upper end of the shank and disposed in substantially rectangular formation is a frame 2 arranged with respect to the shank in a manner whereby the latter 45 depends centrally therefrom as best shown in Figure 1.

The shank 1 is looped upon itself adjacent one end as at 3, and this loop provides the lower stop for limiting the movement of the hammer 4 in its lowermost position, while the

frame 2 limits the hammer in its uppermost position.

The hammer is in the nature of a sleeve 55 formed from weighted material such as a composition including lead or the like, and surrounds the shank for slidable movement thereon between the frame and the loop 3 as will be apparent. The shank extends a considerable distance below the loop 3 and terminates in a penetrating point 5.

The frame 2 has secured to its longitudinal portions a strip of material 6 which has its longitudinal edges curved upon themselves and wrapped about the longitudinal portions of the frame as best shown in Figure 2. The lower longitudinal edge of the strip is recessed so as to accommodate for the passage of the shank 2 from its juncture with the frame, the shank and frame being formed integral as shown. The strip 6 is adapted to 65 have printed or otherwise formed thereon advertising matter of any description, and the strip as well as the frame 2 acts in the capacity of a handle during the use of the pick.

From the above description and disclosure 75 of the drawings, it will be obvious that I have provided an ice pick that is capable of chipping ice in pieces of substantially a size desired, as the penetrating point is positioned on a cake or piece of ice and held thereon through the instrumentality of the handle, thence the hammer 4 is reciprocated upon the portion of the shank between the frame and loop 3 to provide a hammering action upon the loop 3, and such action will result in the 80 penetrating point passing into the ice which will break from a line from the penetrating point.

It is thought from the foregoing description that the advantages and novel features 85 of my invention will be readily apparent.

I desire it to be understood that I may make changes in the construction and in the combination and arrangement of the several parts, provided that such changes fall within the scope of the appended claim.

What I claim is:

An ice pick of the character described comprising a shank, a rectangular frame formed at right angles with one end thereof, a strip 90

of material having its longitudinal edges curved upon themselves and disposed about the longitudinal portions of the frame, said strip and frame providing a handle for the
5 pick, a penetrating point formed at the opposite end of said shank, said shank being looped upon itself adjacent the penetrating point to provide a stop, and a weighted sleeve in the nature of a hammer mounted for slide-
10 able movement on that portion of the shank between the looped portion and handle for engagement with the looped portion to set up a hammering action.

In testimony whereof I affix my signature.

15
